UNITED STATES PATENT OFFICE

119,753

DESIGN FOR A CLOTHESLINE REELING UNIT

George L. Hunt, Chicago, Ill.

Application January 6, 1940, Serial No. 89,329

Term of patent 7 years

To all whom it may concern:

Be it known that I, George L. Hunt, a citizen of the United States and a resident of Chicago, county of Cook, and State of Illinois, have invented a new, original, and ornamental Design for a Clothesline Reeling Unit, of which the following is a specification, reference being had to the accompanying drawing, forming a part thereof.

Figure 1 is a top plan view of a clothesline reeling unit, showing my design.

Figure 2 is a side elevational view; and
Figure 3 is an end elevational view thereof;

Figure 4 is a front elevational view;

Figure 5 is a side elevational view; and

Figure 6 is a rear elevational view of the pulley element of the clothesline reeling unit shown in Figure 1.

I claim:

The ornamental design for a clothesline reeling unit, substantially as shown and described.

GEORGE L. HUNT.
